UNITED STATES PATENT OFFICE.

HOWARD D. COLMAN AND BURT A. PETERSON, OF ROCKFORD, ILLINOIS, ASSIGNEES,
BY MESNE ASSIGNMENTS, TO EDGAR S. NETHERCUT, OF EVANSTON, ILLINOIS.

WINDER.

Application filed September 11, 1919. Serial No. 323,074.

This invention relates to means for supporting a yarn mass for rewinding. The invention has special, although not exclusive, reference to means for supporting a 5 bobbin that is to be rewound in an automatic winder. For a disclosure of one type of automatic winder to which the present invention is applicable, reference may be had to the Colman Patent No. 1,267,977 dated 10 May 28, 1918. The patent just mentioned discloses means for supporting bobbins which rotate to deliver the yarn. It has been found that if the bobbins are supported so that the yarn may be unwound from 15 the end of the bobbin, a greatly increased speed of winding is attainable.

A particular object of the present invention is to provide means for supporting the bobbin for the drawing off of the yarn from 20 the end of the bobbin, together with automatically-operable means for discharging the spent bobbin and for placing a reserve bobbin in running position.

In the accompanying drawings, Figure 1 25 is a fragmentary sectional view taken transversely of a winder embodying the features of this invention. Fig. 2 is a front view of the bobbin-holder. Fig. 3 is a view of the devices on the traveling mechanism for 30 operating the bobbin-holder. Fig. 4 is a plan view taken in the plane of line 4—4 of Fig. 2. Fig. 5 is a vertical sectional view taken in the plane of line 5—5 of Fig. 4. Fig. 6 is a view taken in the plane of line 35 6—6 of Fig. 5, but showing the parts in a different position. Fig. 7 is a fragmental view illustrating the thread guide.

In the drawings A is an active or running bobbin. B is a reserve bobbin. C is a 40 clamp for the end of the thread of the reserve bobbin. D is a bridge across which the reserve thread extends, and E is a portion of a mechanism arranged to travel along the winder. In Fig. 1, the traveling mechanism may be assumed to be moving 45 away from the observer.

The embodiment herein shown of the invention comprises a casing 1 which is rigidly secured to the framework of the winder 50 in a suitable manner. The casing 1 com-

prises two vertical side walls 2 and 3 rigidly secured together.

In order to reduce the resistance of the air to the unwinding of yarn from the bobbin A, said bobbin is enclosed within a tube or 55 cylindrical casing 4 comprising two approximately semi-cylindrical sections. The section 5 is rigidly mounted in the inner or rear portion of the casing 1. The section 6 is rigidly secured to a rock shaft 7 which 60 is mounted in suitable bearings in the casing 1. As indicated in Fig. 6 the hinged section 6 of the casing 4 may be swung aside to permit the spent bobbin to drop out of the casing 4 and to allow a reserve bobbin 65 to be placed in said casing. The rear portion of the casing 1 is enlarged at one side as shown at 8 to accommodate the section 6. A torsion spring 9 normally holds the section 6 in closed position. 70

When yarn is being drawn off from the end of a bobbin in unwinding, the resistance of the air to the ballooning strand of yarn is considerable. By enclosing the bobbin in a casing the air in the casing is caused to 75 circulate in the direction of rotary movement of the ballooning strand of yarn so that the resistance to said strand is materially reduced. This results in a lower and more uniform tension upon the yarn being 80 unwound and consequently a higher speed of unwinding can be attained with less danger of breakage of the yarn.

Any suitable means may be provided to guide the running thread as it leaves the 85 casing 4. Herein the casing section 5 is provided with an upper end wall 10. In said end wall is a thread guide opening 11 located axially of the casing 4, said opening being partially defined by a finger 12. 90 The opening 11 communicates with a flaring throatway 13. On the end wall 10 is secured a plate 14 (Fig. 4) having a finger 15 which overlaps and extends oppositely to the finger 12. The fingers 12 and 15 are 95 spaced apart as shown in Fig. 5 to permit the thread to pass laterally between said fingers and enter the opening 11. After the thread has entered said opening it is retained therein by the fingers 12 and 15. The 100

section 6 of the casing 4 has an upper end wall 16 which, when in operative position, also serves to retain the running thread in the opening 11.

5 The butt of the active bobbin is centered between two concave jaws 17 and 18 fixed to the sections 5 and 6, respectively, of the casing 4. The active bobbin is mounted upon a skewer 19 adapted to enter the lower 10 portion of the bore of the bobbin. Said skewer is fixed to an arm 20 rigidly secured to a spindle 21 which is mounted in bearings 22 on the casing 1. Attached to the lower portion of the spindle 21 is a stud 15 23 which lies within a cam slot 24 formed in a plate 25 fixed to the casing 1. A coiled spring 26 (Fig. 5) normally holds the spindle 21 in the position shown in said view. An arm 27 is pivoted to the casing 20 1 at 28 and has its rear end portion overlying the upper end of the spindle 21. Rigid with the arm 27 is an arm 29 which is arranged to be engaged by a cam bar F forming part of the traveling mechanism E.

25 The cam slot 24 is of such form that when the cam bar F acts upon the arm 29 the spindle 21 is first moved downward to withdraw the skewer 19 from the bobbin A and the casing 4, and is then turned to swing the 30 arm 20 and skewer 19 aside so as to be out of the way of the bobbin A when the latter is allowed to fall from the casing 4.

The reserve bobbin B lies within a pocket 35 30 which is mounted upon a pivot 31. The pocket 30 is provided with a bottom or support 32 and a concave seat or jaw 32^a for the butt of the reserve bobbin. Said bobbin pocket 30 is notched or cut away, as shown at 33 in Figs. 4 and 6, to provide 40 clearance for the skewer 19.

The pocket 30 has an upper end wall 34 serving as an abutment against which the bobbin is pushed during the skewering of the bobbin. When the pocket 30 is swung 45 to transfer the reserve bobbin to the casing 4 the edge of the end wall 34 carries the reserve thread into the flaring throatway 13, the winding tension serving to complete the movement of the thread into the guide 50 opening 11.

Normally the reserve bobbin pocket 30 stands in the position shown in Fig. 5 with the upper portion of the pocket resting against the cross-piece 35 of the casing 1, the 55 pocket being sufficiently inclined to retain the bobbin placed therein by the operator.

The means herein shown for swinging the pocket 30 to carry the bobbin to the running position comprises a cam bar G mounted on 60 the traveling mechanism E, said cam bar being arranged to act upon a crank arm 36 which is pivoted upon the axis 28 and is rigid with a crank arm 37. The arm 37 is connected by means of a link 38 with a 65 crank arm 39 fixed to the bobbin pocket 30.

40 is a contractile spring acting on the arm 37 to return the reserve bobbin pocket to normal position after the passage of the cam bar G.

On the upper end of the rock shaft 7 is 70 a crank arm 41 which is arranged to be engaged by a cam bar or flange H on the traveling mechanism E.

On the casing section 6 is a flange 42. When the section 6 is in closed position, the 75 flange 42 partly closes the space between said section and the bottom 32. When the operator drops a bobbin into the pocket 30, the flange 42 prevents the bobbin from entering said space. If the butt of the bobbin 80 should rest upon said flange, the section 6 will push the bobbin onto the bottom 32 when the section 6 is swung open.

Assuming the parts to be in the position shown in Fig. 5 the operation is as follows: 85 By the time the traveling mechanism E reaches the bobbin holder, the bobbin A will have been completely unwound or the thread will have broken, but if the thread is still running, the mechanism E will break the 90 thread. In the travel of the mechanism E the cam bar F engages the arm 29 and causes the skewer 19 to be withdrawn from the bobbin A and swung aside. If the skewer should tend to stick in the bobbin, the latter 95 is held by the jaws 17 and 18 during the withdrawal of the skewer. The dwell portion F' of the cam bar F holds the skewer in the withdrawn position for the necessary 100 length of time. The cam bar or flange H then engages the crank arm 41 and causes the section 6 of the casing 4 to be swung into the position shown in Fig. 6, whereupon the spent bobbin drops out of the casing 4, the bobbin being received upon a conveyor I (Fig. 1) or otherwise disposed of.

The dwell portion of the cam flange H holds the pivoted section 6 in the position shown in Fig. 6 for the time being. The cam bar G of the traveling mechanism then engages 110 the arm 36 and causes the pocket 30 to swing rearwardly into the position shown in Fig. 6, thus placing the reserve bobbin B in the fixed portion 5 of the casing 4. The butt of the bobbin B then stands between the jaws 115 17 and 32^a and is thus centered for the entry of the skewer. The dwell portion G' of the cam bar G holds the bobbin pocket 30 in this position until the cam bar F has left the arm 29 and allowed the spring 26 to move the skewer 19 into engagement with the bobbin B.

In the continuing travel of the mechanism E the cam bar G leaves the crank arm 36, whereupon the spring 40 restores the pocket 30 to normal position. The cam flange H then leaves the crank arm 41, whereupon the torsion spring 9 swings the section 6 of the casing 4 into closed position.

While the traveling mechanism E is pass- 130

ing the bobbin holder the thread-uniting mechanism effects the joining of the reserve thread to the end of the exhausted thread and causes winding to be resumed after the section 6 of the casing 4 has been restored to normal position. After the traveling mechanism has passed the bobbin-holder the operator drops a reserve bobbin into the space between the walls 2 and 3, the bobbin 10 coming to rest in the pocket 30, and puts the end of the reserve thread in the clamp C.

The bobbins shown in Fig. 5 are ordinary warp bobbins having warp-wound yarn masses thereon. It has been found that a higher winding speed can be attained with warp-wound bobbins than with filling-wound bobbins, as at the higher speeds the layers of filling-wound yarn tend to slough off. 20 The present invention, however, is not limited to any particular type of yarn mass.

While the present embodiment of the invention has been described in considerable detail such description has been given for the purpose of affording a clear understanding of the construction and mode of operation of the form of bobbin-holder and bobbin-holder-operating devices herein illustrated and not for the purpose of defining the invention. As indicated by the scope of the appended claims, the invention is susceptible of embodiment in widely different forms.

Embodiments of the general principles of our invention are disclosed in our companion application Serial No. 323,075, and in application Serial No. 323,194 filed by Burt A. Peterson. Those embodiments are within the intended scope of the principal claims 40 hereinafter set forth.

In the following claims the terms "thread" and "yarn" are intended to include all other generally similar material, and the terms "yarn mass", "bobbin" and "yarn mass carrier" are intended to be broadly construed.

We claim as our invention:

1. In a winder, the combination of a casing having a movable section, a skewer insertable into the end of the casing, a movable reserve bobbin pocket, a mechanism arranged to travel along the winder and having means to withdraw the skewer, open the movable section of the casing and move the reserve bobbin pocket, means controlled by said mechanism for returning the skewer to operative position, and means controlled by said mechanism for closing the movable section of the casing.

60 2. In a winder, the combination of a casing having a movable section, a skewer insertable into the end of the casing, a movable reserve bobbin pocket, means to withdraw the skewer, means to open the movable section of the casing, means to move the

reserve bobbin pocket, means for returning the skewer to operative position, and means for closing the movable section of the casing.

3. In a winder, the combination of a skewer, a bobbin centering means, a movable reserve bobbin pocket, and a mechanism arranged to travel along the winder and having means to disengage the skewer, from a spent bobbin, to open the bobbin centering means and move the reserve bobbin pocket to place a reserve bobbin in position to be skewered.

4. The combination of a bobbin-containing casing having an opening in one end, a spindle reciprocable longitudinally of the casing, 80 an arm on said spindle, a skewer on said arm adapted to enter said opening, means for reciprocating said spindle, and means for turning the spindle during its reciprocation to cause lateral movement of the skewer. 85

5. The combination of a bobbin-containing casing, a spindle reciprocable longitudinally of the casing, an arm on said spindle, a skewer on said arm, means for reciprocating said spindle, and means for turning the spindle to cause lateral movement of the skewer. 90

6. The combination of bobbin-centering elements, a reciprocable spindle, an arm on said spindle, a skewer on said arm adapted to pass between said centering elements, 95 means for reciprocating said spindle, and means for turning the spindle to cause lateral movement of the skewer.

7. The combination of bobbin-centering elements, a reciprocable spindle, an arm on 100 said spindle, a skewer on said arm adapted to pass between said centering elements, and means for reciprocating said spindle.

8. The combination of a bobbin-containing casing divided into two longitudinal 105 sections, one section being stationary and the other being movable, a bobbin-supporting skewer adapted to enter one end of the casing, means for placing a bobbin in the casing, means for operating the skewer, and means for opening and closing the movable section of the casing.

9. The combination of a bobbin-containing casing divided into two longitudinal 115 sections, one section being stationary and the other being movable, a bobbin skewer, means for placing a bobbin in the casing, means for operating the skewer to engage the bobbin, and means for opening and closing the movable section of the casing. 120

10. The combination of a bobbin-containing casing, a bobbin skewer movable into and out of the casing through one end of the casing, and means for placing a bobbin in the casing.

11. The combination of means for supporting a yarn carrier in approximately vertical position for the drawing of yarn off the upper end of the carrier, said means including means to center the butt of the car- 130

- rier and a skewer to enter the lower end of the bore of the carrier, and mechanism to insert and remove the skewer, said mechanism including means to swing the skewer out from beneath the carrier.
12. The combination of a skewer for supporting a yarn carrier in approximately vertical position for the drawing of yarn off the upper end of the carrier, and mechanism to insert and remove the skewer, said mechanism including means to swing the skewer out from beneath the carrier.
13. In a winder, the combination of means for supporting a yarn carrier in approximately vertical position for the drawing of yarn off the upper end of the carrier, said means including means to center the butt of the carrier, and automatically-actuated means to operate the centering means to center and release the carrier.
14. The combination of a skewer, means to insert the skewer into a yarn carrier, a centering means for the butt of the carrier, and means to operate the centering means to center and release the carrier.
15. In a winder, the combination of a skewer for supporting a yarn carrier in approximately vertical position for the drawing of yarn off the upper end of the carrier, a centering means for the butt of the carrier, and automatically-actuated means to withdraw the skewer and then operate the centering means to release the carrier.
16. The combination of a bobbin-containing casing divided into two longitudinal sections one of which is stationary and the other pivoted, a thread guide at one end of the stationary section, and a part on the pivoted section adapted to move a thread into position close to said thread guide.
17. The combination of a bobbin-containing casing divided into two longitudinal relatively movable sections, and a thread guide at one end of the casing, one of the casing sections being adapted to move a thread into position close to said thread guide.
18. The combination of a bobbin-containing casing divided into two relatively movable sections, a thread guide adjacent to the casing, and means adapted to move a thread into position close to said thread guide.
19. The combination of a bobbin-containing casing, and a pocket movable to place a bobbin in said casing, that portion of the casing which is adjacent to the pocket being withdrawable.
20. The combination of a bobbin-containing casing divided into two longitudinal relatively movable sections, and a pivoted reserve-bobbin pocket adapted to carry a bobbin laterally into the casing.
21. A winder having, in combination, a skewer for holding a bobbin while the latter is being unwound, means for laterally mov-
- ing a full bobbin into axial alinement with the skewer; and means for moving the skewer into the bobbin.
22. A winder having, in combination, a skewer for holding a bobbin while the latter is being unwound, a guide for the thread to be unwound from said bobbin, means for laterally moving a full bobbin into operative relation to the guide, and means for inserting the skewer into the bobbin.
23. The combination of a skewer for a yarn carrier, a casing to enclose the carrier, and devices to place a yarn carrier in said casing and engage the skewer with the carrier.
24. The combination of a skewer for a yarn carrier, a casing to enclose the carrier, and devices to move a yarn carrier laterally into said casing and move the skewer into the carrier.
25. A winder having, in combination, means for supporting a yarn mass at one end for the drawing of yarn upwardly off the other end of the yarn mass, an elongated pocket having an open side to receive a reserve yarn mass, the latter lying loosely within and extending longitudinally of the pocket, and the pocket being pivoted at its lower end, and means to swing the pocket to carry the reserve yarn mass to said supporting means.
26. A winder having, in combination, means for supporting a bobbin with its axis extending vertically for the drawing of yarn off the upper end of the bobbin, a reserve bobbin pocket pivoted to swing from an inclined position forward of the supporting means to a vertical position alongside said supporting means, and walls at opposite sides of the path of movement of said pocket, the arrangement being such that a bobbin may be dropped endwise into the space between said walls and thus into said pocket.
27. A winder having, in combination, a casing within which a bobbin may be supported with its axis extending vertically for the drawing of yarn off the upper end of the bobbin, said casing comprising a front section hinged to swing aside, a reserve bobbin pocket pivoted to swing from an inclined position forward of the supporting means to a vertical position coinciding with the normal position of said hinged casing-section, and walls at opposite sides of the path of movement of said pocket, the arrangement being such that a bobbin may be dropped endwise into the space between said walls and thus into said pocket.
28. The combination of a casing comprising a fixed section and a movable section, coacting bobbin-centering elements on one end of said sections, and a skewer movable into and out of said end of the casing.
29. The combination of a casing comprising a fixed section and a movable section,

- and coaxing bobbin-centering elements on said sections adapted to engage the butt of the bobbin.
30. The combination of a bobbin-containing casing divided into two longitudinal sections, one section being stationary and the other being movable, and coaxing bobbin-centering elements on one end of said sections.
10. 31. A winder having, in combination, a skewer for supporting a bobbin with its axis extending vertically for the drawing of yarn off the upper end of the bobbin, a reserve bobbin pocket pivoted to swing from an inclined position forward of the normal position of the skewer to a vertical position, two coaxing butt-centering elements, one located stationarily behind a normal position of the skewer, and the other attached to said pocket, the skewer being movable into engagement with a bobbin held between said centering elements.
25. 32. In a winder, the combination of a skewer, a movable reserve bobbin pocket, a mechanism arranged to travel along the winder and having means to move the skewer out of operative position, and move the reserve bobbin pocket to place a bobbin in position to be skewered, means controlled by said mechanism for engaging the skewer with the bobbin, and means controlled by said mechanism for returning the pocket to normal position.
35. 33. In a winder, a reserve bobbin pocket pivoted at its lower end to swing from an inclined forward position to a vertical position and walls at opposite sides of the path of movement of said pocket, the arrangement being such that a bobbin may be dropped into the space between said walls and thus into said pocket.
40. 34. A winder having, in combination, a bobbin skewer, a carriage arranged to travel past the skewer, and cooperating instrumentalities connected to said carriage and skewer for replacing a spent bobbin on the skewer with a full bobbin, said instrumentalities including means to move the skewer to disengage it from the spent bobbin.
50. 35. In a winder, the combination of a bobbin-skewer, and means arranged to travel along the winder for moving the skewer to engage and support a full bobbin.
55. 36. In a winder, the combination of a bobbin-skewer, means to center the butt of a bobbin, and means arranged to travel along the winder for operating the skewer and the centering means to center and skewer a bobbin.
60. 37. The combination of a centering means for a bobbin, a skewer to enter the bore of a bobbin held in the centering means, and means to operate the centering means and the skewer to center and skewer a bobbin.
65. 38. In a winder, the combination of a bobbin-skewer, centering means for the butt of a bobbin, and means arranged to travel along the winder for operatively associating the skewer and the centering means with a bobbin.
70. 39. A winder having, in combination, means for supporting a yarn mass for the drawing of yarn off the end of the yarn mass, and devices for operatively associating a yarn mass with said supporting means.
75. 40. A winder having, in combination, means for supporting a yarn mass for the drawing of yarn off the end of the yarn mass, a support in front of the first mentioned supporting means for holding a reserve yarn mass, and means arranged to travel along the winder for operatively associating said reserve yarn mass with said first-mentioned supporting means.
80. 41. The combination of a pocket into which the operator may lay a bobbin, a skewer, and devices to effect engagement of the bobbin by the skewer after the bobbin has been placed in position in the pocket.
85. 42. In a winder, the combination of a container for the bobbin being unwound, a skewer adapted to support a bobbin in the container during the unwinding operation, and means for causing separation of the skewer and the bobbin, and for causing relative lateral movement between the container on the one hand, and the skewer on the other hand.
90. 43. The combination of a stationary casing section; and a movable casing section and a movable reserve bobbin holder arranged alternately to move into and out of position adjacent to the stationary section, said stationary section in conjunction with either of said movable elements forming an enclosure for a full bobbin.
95. 44. The combination of a stationary casing section; and a movable casing section and a movable reserve bobbin holder arranged alternately to move into and out of position adjacent to the stationary section, said stationary section in conjunction with either of said movable elements forming an enclosure for a full bobbin, each of said movable elements having a bobbin-butt-engaging jaw, and the stationary section having a similar coaxing jaw.
100. 45. The combination of a stationary casing section; and a movable casing section and a movable reserve bobbin holder arranged alternately to move into and out of position adjacent to the stationary section, said stationary section in conjunction with either of said movable elements forming an enclosure for a full bobbin, each of said movable elements having a bobbin-butt-engaging jaw, and the stationary section having a similar coaxing jaw, and a skewer to enter the butt of the bobbin, said skewer

being movable into and out of the end of said enclosure.

46. A winder having, in combination, a casing to surround a bobbin being unwound, there being an annular space for the unwinding thread between the casing and the bobbin, and a skewer to support the bobbin, said skewer being movable into and out of one end of the casing whereby to insert the skewer into or withdraw it from a bobbin in said casing.

47. A winder having, in combination, a casing to surround a bobbin being unwound, there being an annular space for the unwinding thread between the casing and the bobbin, and a skewer to support the bobbin, said skewer and casing being relatively movable in the direction of the axis of the bobbin whereby to insert the skewer into or withdraw it from a bobbin in said casing.

48. A winder having, in combination, a bobbin skewer, a reserve bobbin pocket in front of the skewer, a carriage arranged to travel past said skewer and pocket, and cooperating instrumentalities connected with said carriage, skewer and pocket for replacing a spent bobbin on the skewer with a full bobbin from said pocket.

49. A reserve bobbin holder for a winder, said holder being adapted to contain a bobbin lying loosely therein, said holder having a butt-supporting portion provided with an opening alined with the bore of the bobbin, and a stop portion fixed to the holder adjacent to the tip of the bobbin to limit endwise movement to the bobbin.

50. A winder having, in combination, a stationary centering jaw, and a movable reserve bobbin holder having a jaw adapted to coact with the stationary jaw to center the bobbin.

In testimony whereof we have hereunto set our hands.

HOWARD D. COLMAN.
BURT A. PETERSON.

CERTIFICATE OF CORRECTION.

Patent No. 1,727,534.

Granted September 10, 1929, to

HOWARD D. COLMAN ET AL.

It is hereby certified that error appears in the printed specification of the above numbered patent requiring correction as follows: Page 5, strike out lines 71 to 75, comprising claim 39; same page lines 76, 85, 90, 99, 107, 119, and page 6, lines 3, 12, 21, 29 and 37, for claim numerals "40, 41, 42, 43, 44, 45, 46, 47, 48, 49 and 50" read "39, 40, 41, 42, 43, 44, 45, 46, 47, 48 and 49"; page 6, claim 49 now 48, line 36, for "to" read "of"; and that the said Letters Patent should be read with these corrections therein that the same may conform to the record of the case in the Patent Office.

Signed and sealed this 29th day of October, A. D. 1929.

(Seal)
